UNITED STATES PATENT OFFICE

ALFRED O. KELLOGG, OF PELHAM MANOR, NEW YORK

COMBINED DAYLIGHT AND ILLUMINATED SIGN

Application filed September 8, 1928. Serial No. 304,721.

My present invention relates to combined day and night signs, particularly electrically illuminated signs which are adapted to serve with equal effectiveness as signs by day and also by night, and aims to devise signs of the general character designated which are simple in construction, which may be simply and economically fabricated and assembled, which are highly effective both by day and by night, and which, in certain of their embodiments, make use of one or more shifting or fluctuating colors or color combinations, thus producing novel and arresting effects rendering the signs of the present invention particularly useful and effective for advertising purposes. Other objects and advantages of the devices of the present invention will in part be pointed out in detail hereinafter and will in part be obvious to those skilled in the art to which the present invention relates.

In the accompanying specification I shall describe, and in the annexed drawing show, an illustrative embodiment of the present invention. It is, however, to be clearly understood that my invention is not limited to the specific embodiment thereof herein shown and described for purposes of illustration only.

Referring to the drawings, in which I have shown the aforesaid illustrative embodiment of the present invention:

Fig. 1 is a perspective view of the assembled device constituting such embodiment;

Fig. 2 is a cross-sectional view of the same taken along line 2—2 of Fig. 3 of the drawing;

Fig. 3 is a longitudinal sectional view of the device as a whole;

Fig. 4 is a plan view of one of the socket bases embodying one form of light-shifting or light-fluctuating device; and

Fig. 5 is a perspective view of the sign plate proper, one end of the paster forming a part of such sign plate being shown lifted away from the glass or equivalent support to make its construction clearer.

Referring now to the aforesaid illustrative embodiment of the present invention, and with particular reference to the draw-

ings illustrating the same, 10 indicates, generally, the housing for the sign, this housing consisting, for example, of a box-like structure having the bottom portion 11 and the end walls 12 and 13. The end walls 12 and 13 are preferably somewhat tapered at their upper ends, here generally designated by reference character 14, for cooperation with the other portions of the housing now to be described. 15 indicates the lower back portion of the housing. The parts 11, 12, 13, 14 and 15 thus far described may be made of wood or other suitable material and assembled in any desired manner, as will be readily apparent to those skilled in the art to which the present invention relates.

Cooperating with the parts of the housing thus far described is a front portion 16 below which is defined an opening 17 through which the sign proper is displayed in a manner which will shortly be described. 18 indicates the top of the housing, the same being preferably provided with a series 19 of ventilating apertures, the top 18 being hinged at 20 to the upper back portion 31 which is in turn hinged at 22 to the lower back portion 15. Means, generally designated by reference character 23 and comprising, for example, a hook 24 pivotally attached to the edge of the top portion 18 and an eyelet 25 fixedly positioned in the front portion 16, may be provided for keeping the top portion 18 and the upper back portion 21 in closed position during the use of the sign.

The sign plate proper, here generally designated by reference character 26, may be made in various manners. I prefer, however, to make the same substantially as follows: 27 indicates a plate of glass or equivalent material. If glass is used, I may use either opalescent, frosted, ground or stippled glass. Associated with the glass or equivalent support 27 is a paster 28 preferably in the form of a thin paper sign printed in reverse, that is, having a series of letters or other representations 29 left white in translucent or transparent form on a black field generally designated by reference character 30. The paster or paper sign 28 may be pasted onto the glass or equivalent sup-

porting plate 27 by a thin paste solution or by means of any other suitable adhesive.

The sign 26 may be inserted into the housing 10 and suitably supported therein by means of the slot or channels 31 and 32 with which the end walls 12 and 13 are respectively provided. However, any other suitable means may be employed for suitably positioning and supporting the sign 26.

Forming a part of the device is a mirror here generally designated by reference character 33. The mirror is intended to receive light transmitted through the sign 26 from the illuminating system generally designated by reference character 34. The mirror 33 should be of such dimensions as to receive with ample margins the image from the sign 26 and to deliver the same to the eye of the observer at a convenient angle, depending upon the angle of incidence of the line of vision of the observer onto the mirror 33, in accordance with well-known optical principles which need not be discussed here and which are familiar to those skilled in the art to which the present invention relates.

Coming now to the lighting system 34, I may use for the same one or more lamps, preferably electric bulbs of the usual sort, in one or more colors, preferably a plurality of colors, such as three colors. As more clearly shown in Fig. 3 of the drawings, I have employed three such electric lamps, generally designated by reference characters 35, 36 and 37, of which one of the lamps, such as the lamp 35, may be red, another of the lamps, such as the lamp 36, may be blue, and the remaining lamp 37 may be of still another color, such as green. The lamps 35, 36 and 37 may be suitably connected, as in parallel, by means of the wires 38 and 39 and the sockets 40, 41 and 42, respectively, with a cable 43 connected with a plug or other suitable connection device, not here deemed necessary to be shown, for connection with the usual electrical lighting system of the structure in which the sign is to be employed. It may here be stated that I may provide additional ventilating apertures 21' in the upper back portion 21 for ventilating the portion of the structure in which the illuminating system 34 is located, since, as will be readily apparent to those skilled in the art to which the present invention relates, such illuminating system generates heat and it is on the basis of the heat generated, in one form of the invention, that the shifting or fluctuating lighting effects are obtained.

Referring now to Fig. 4 of the drawings in which I have illustrated one of the lamp sockets, such as the socket 40, 44 indicates a supporting base made of suitable insulating material carrying the usual threaded socket member 45 having the spring contact 46 con-

nected with one of the wires, such as the wire 38. The socket portion 45 is itself connected with the remaining wire 39 by means of a thermostatic contact generally designated by reference character 47. The arrangement is such that as the temperature generated by the bulb 35 varies beyond a certain point, either high or low, as the case may be, the circuit, through the lamp is either made or broken, as desired.

It may here be stated that other means for producing a shifting or fluctuating light effect for each of the electric lamps 35, 36 and 37, or their equivalents, may be utilized. It may here also be stated that in order to get the greatest variety of color combinations and effects, the thermostatic contacts for the sockets 40, 41 and 42 may be set for different temperatures or for different temperature ranges so that the bulbs are on at different times and for different lengths of time. This will bring the utmost variation into the illuminating system and produce the greatest variety of color effects. By way of explanation, it may here be stated that the thermostatic contact 47 comprises the substantially fixed contact 47' and the variable contact 47'', each of these carrying a contact point, not here deemed necessary to be shown, which, by their contact, close the circuit through the particular electric light bulb and by their coming out of contact, break such circuit.

This completes the description of the construction of the aforesaid illustrative embodiment of the present invention. The manner of assembling such embodiment will, it is believed, fully appear from the foregoing description. The mode of use and operation of such embodiment will likewise, it is believed, fully appear from the foregoing description but may be briefly summarized as follows: After the paster 28 has been applied to the ground glass 27, the sign is ready for insertion in the housing by means of the slots 31 and 32. It may here be stated that new or additional pasters may be readily applied by the removal of the original paster 28, thus rendering it possible to change the reading of the sign readily and in a very simple manner. This is a feature of great importance in adapting the sign for a wide variety of uses.

Assuming now that the parts 35, 36 and 37 are red, blue and green, respectively, and that the thermostatic contacts of the sockets 40, 41 and 42 are set so as to open and close at different temperatures and at different time intervals, the illuminating system 34 requires merely to be connected with the housing or other lighting circuit by means of a suitable plug or equivalent connecting device in a manner which will be readily apparent to those skilled in the art to which the present invention relates.

Thereupon the lights 35, 36 and 37 will be on at different times and for different time intervals, sometimes separately, sometimes two together in varying combinations, and sometimes all three together. The time intervals will vary almost indefinitely due to the changing temperature conditions as a result of the unequal intervals during which the lamps 35, 36 and 37 are respectively illuminated. The varying light effects thus produced are transmitted through the sign 28 and reflected in the mirror 33 at such an angle as to most effectively reach the eye of the beholder.

This completes the description of the mode of use and operation of the aforesaid illustrative embodiment of the present invention. It will be noted that such embodiment is simple in construction and may be conveniently, economically and effectively fabricated, assembled and utilized. Signs may be changed at will and modified in a very simple and effective manner. An almost endless variety of color combinations is rendered possible by means of the present invention. At the same time the sign is almost as effective by day as it is by night and otherwise is admirably adapted for the purposes for which it is intended. Other superiorities and advantages of the devices of the present invention, particularly as exemplified in the aforesaid illustrative embodiment of the same, will readily occur to those skilled in the art to which the present invention relates.

What I claim as my invention is:

1. A sign comprising a translucent glass or equivalent supporting plate in combination with an opaque paper or equivalent paster adhesively carried by said plate and bearing a transparent legend thereon so arranged as to cause an inverse image of the legend on a mirror, a light causing said image, said light coming from the opposite side of the plate from the mirror, and being of a plurality of irregularly changing colors.

2. A sign comprising a translucent glass or equivalent supporting plate in combination with an opaque paper or equivalent paster adhesively carried by said plate and bearing a transparent legend thereon so arranged as to cause an inverse image of the legend on a mirror, a light causing said image, said light coming from the opposite side of the plate from the mirror, and being of a plurality of thermostatically changing colors.

3. A combined electrically illuminated day and night sign comprising, in combination, a housing, a translucent sign carried by said housing and comprising a translucent glass or equivalent supporting plate and an opaque paper or equivalent paster carried by said plate and bearing a trans-

parent legend thereon, electric illuminating means within said housing for transmitting light consisting of a plurality of distinct irregularly changing colors through said translucent sign, and a mirror so disposed within said housing as to reflect light transmitted through said translucent sign to the eye of an outside observer.

4. A combined electrically illuminated day and night sign comprising, in combination, a housing, a translucent sign carried by said housing and comprising a translucent glass or equivalent supporting plate and an opaque paper or equivalent paster carried by said plate and bearing a transparent legend thereon, electric illuminating means within said housing for transmitting light consisting of a plurality of distinct colors through said translucent sign, and a mirror so disposed within said housing as to reflect light transmitted through said translucent sign to the eye of an outside observer, said electric illuminating means comprising a plurality of thermostatically controlled electric lighting units.

5. A combined electrically illuminated day and night sign comprising, in combination, a housing, a translucent sign carried by said housing and comprising a translucent glass or equivalent supporting plate and an opaque paper or equivalent paster carried by said plate and bearing a transparent legend thereon, electric illuminating means within said housing for transmitting light consisting of a plurality of distinct colors through said translucent sign, and a mirror so disposed within said housing as to reflect light transmitted through said translucent sign to the eye of an outside observer, said electric illuminating means comprising a plurality of thermostatically controlled electric lighting units.

6. A combined electrically illuminated day and night sign comprising, in combination, a housing, a translucent sign carried by said housing and comprising a translucent glass or equivalent supporting plate and an opaque paper or equivalent paster carried by said plate and bearing a transparent legend thereon, electric illuminating means within said housing for transmitting light consisting of a plurality of distinct colors through said translucent sign, and a mirror so disposed within said housing as to reflect light transmitted through said translucent sign to the eye of an outside observer, said electric illuminating means comprising a plurality of electric lighting units of different colors and means for separately regulating the flow of current to each of said electric lighting units.

7. A combined electrically illuminated day and night sign comprising, in combination, a housing, a translucent sign carried by said housing and comprising a translu-

- cent glass or equivalent supporting plate and an opaque paper or equivalent paster carried by said plate and bearing a transparent legend thereon, electric illuminating means within said housing for transmitting light consisting of a plurality of distinct colors through said translucent sign, and a mirror so disposed within said housing as to reflect light transmitted through said translucent sign to the eye of an outside observer, said electric illuminating means comprising a plurality of electric lighting units of different colors and means for separately regulating the flow of current to each of said electric lighting units.
8. A combined electrically illuminated day and night sign comprising, in combination, a housing, a translucent sign carried by said housing and comprising a translucent glass or equivalent supporting plate and an opaque paper or equivalent paster carried by said plate and bearing a transparent legend thereon, electric illuminating means within said housing for transmitting light consisting of a plurality of distinct colors through said translucent sign, and a mirror so disposed within said housing as to reflect light transmitted through said translucent sign to the eye of an outside observer, said electric illuminating means comprising a plurality of electric lighting units of different colors and thermostatic means for separately regulating the flow of current to each of said electric lighting units, the thermostatic means for separately regulating each of said electric lighting units being set to be operated to make and break the circuit through the respective electric lighting units at different time intervals.
9. A combined electrically illuminated day and night sign comprising, in combination, a housing, a translucent sign carried by said housing and comprising a translucent glass or equivalent supporting plate and an opaque paper or equivalent paster carried by said plate and bearing a transparent legend thereon, electric illuminating means within said housing for transmitting light consisting of a plurality of distinct colors through said translucent sign, and a mirror so disposed within said housing as to reflect light transmitted through said translucent sign to the eye of an outside observer, said electric illuminating means comprising a plurality of electric lighting units of different colors and thermostatic means for separately regulating the flow of current to each of said electric lighting units, the thermostatic means for separately regulating each of said electric lighting units being set to be operated to make and break the circuit through the respective electric lighting units at different temperatures.
10. A combined electrically illuminated day and night sign comprising, in combination, a housing, a translucent sign carried by said housing and comprising a translucent glass or equivalent supporting plate and an opaque paper or equivalent paster carried by said plate and bearing a transparent legend thereon, electric illuminating means within said housing for transmitting light consisting of a plurality of distinct colors through said translucent sign, and a mirror so disposed within said housing as to reflect light transmitted through said translucent sign to the eye of an outside observer, said electric illuminating means comprising a plurality of electric lighting units of different colors and thermostatic means for separately regulating the flow of current to each of said electric lighting units, the thermostatic means for separately regulating each of said electric lighting units being set to be operated to make and break the circuit through the respective electric lighting units at different temperatures.
11. A combined electrically illuminated day and night sign comprising, in combination, a housing, a translucent sign carried by said housing and comprising a translucent glass or equivalent supporting plate and an opaque paper or equivalent paster carried by said plate and bearing a transparent legend thereon, electric illuminating means within said housing for transmitting light consisting of a plurality of distinct colors through said translucent sign, and a mirror so disposed within said housing as to reflect light transmitted through said translucent sign to the eye of an outside observer, said electric illuminating means comprising a plurality of electric lighting units of different colors and thermostatic means for separately regulating the flow of current to each of said electric lighting units, the thermostatic means for separately regulating each of said electric lighting units being set to be operated to make and break the circuit through the respective electric lighting units at different time intervals.
12. A combined electrically illuminated day and night sign comprising, in combination, a housing, a translucent sign carried by said housing and comprising a translucent glass or equivalent supporting plate and an opaque paper or equivalent paster carried by said plate and bearing a transparent legend thereon, electric illuminating means within said housing for transmitting light consisting of a plurality of distinct colors through said translucent sign, and a mirror so disposed within said housing as to reflect light transmitted through said translucent sign to the eye of an outside observer, said electric illuminating means comprising a plurality of electric lighting units of different colors and thermostatic means for separately regulating the flow of current to each of said electric lighting units, the thermostatic means for separately regulating each of said electric lighting units being set to be operated to make and break the circuit through the respective electric lighting units at different time intervals.

the thermostatic means for separately regulating each of said electric lighting units being set to be operated to make and break the circuit through the respective electric lighting units at different time intervals and at different temperatures.

5 In testimony, whereof, I have signed my name to this specification this 5th day of September, 1928.

ALFRED O. KELLOGG.
